UNITED STATES PATENT OFFICE

HORACE N. PACKARD, OF MILWAUKEE, WISCONSIN, ASSIGNOR, BY MESNE ASSIGNMENTS, TO CUTLER-HAMMER, INC., A CORPORATION OF DELAWARE

METHOD AND APPARATUS PARTICULARLY APPLICABLE TO MEASUREMENTS OF THE CALORIFIC VALUE OF COMBUSTIBLE GASES

Application filed January 21, 1921. Serial No. 438,954.

This invention relates to a method and apparatus particularly applicable to measurements of the calorific value of combustible gases or other chemically reactive agents although certain features thereof have other advantageous applications.

In my prior patent No. 1,625,277, dated April 19, 1927, are disclosed a method and apparatus wherein constant volumetric proportions of test gas, combustion air and cooling air are delivered under like temperature, pressure and saturation conditions to a device for effecting combustion of the gas and transfer of the heat so liberated to the cooling air, the consequent temperature rise of the latter being indicated, whereby any variation in heating value of the test gas causes a corresponding proportional change in the indicated temperature rise of such cooling air and the latter comprises a measure of the former.

The present invention has among its objects that of providing another method of effecting the foregoing and other results with certain advantages over such former method.

A more specific object is that of providing such a method wherein the necessity of certain corrections of the results of the former method is obviated.

Another object is that of providing such a method wherein a constant temperature rise of the cooling fluid may be maintained thereby minimizing variations in heat loss and facilitating correction or compensation therefor.

Another object is that of providing such a method possessing characteristics which render the same particularly applicable to regulation for constant or other desired temperature effects, either with or without definite ascertainment or indication of values.

Another object is that of providing simple and efficient form of apparatus for performance of such method.

Another object is that of providing an apparatus for carrying out the aforesaid method, wherein compensation is made for possible errors due to temperature variations tending to influence the results thereof.

Other objects and advantages will herein-after appear.

The accompanying drawing illustrates schematically and diagrammatically a proposed form of such apparatus and the same will now be described, it being understood that such apparatus may be modified in numerous ways within the scope of the appended claims.

Following the disclosure of said prior patent, the test gas and combustion air are supplied to a suitable burner for combustion thereof, the cooling fluid being separately supplied to an associated heat exchange device for absorption of the heat so liberated and the consequent temperature rise of said cooling fluid is utilized in effecting the desired indication. Also as in said patent, all of said fluids are supplied under like conditions of temperature, pressure and saturation and in definite proportions by volume. Moreover, the construction and arrangement of the burner and heat exchange device are such as to maintain like temperature of the incoming combustion fluids and the escaping combustion products while preventing intermingling of the cooling fluid with any of the other fluids, whereby the temperature rise of said cooling fluid is a true measure of the total heating value of the test gas.

As distinguished from the former method, it is now proposed to provide for varying the proportions of the supplied test gas and air to compensate for variations in heating value of the gas and responsive to variations in temperature rise of the cooling fluid, whereby such temperature rise is maintained substantially constant and the values of the variations so effected in the proportioning of said fluids constitute a measure of the heating value of such test gas. Also the former method and apparatus have been modified in ways to be hereinafter described to eliminate possible errors including those due to temperature variation which are independent of the combustion.

Referring to the drawing, the same illustrates a burner and associated heat exchange device 1, having the aforesaid structural and functional characteristics and pro-

100

vided with separate intake conduits 2, 3 and 4 for the three fluids aforementioned. Said fluids are supplied to said conduits and thence to the device 1 by means of three 5 pumps including a gas pump 5, a combustion air pump 6 and a cooling air pump 7, and preferably comprising separate wet displacement meter structures located within a common liquid seal comprising water 10 or other liquid to be maintained at a substantially constant level within a tank 8. Said pumps are further adapted to be power driven by a suitable motor 9. The power connection of pumps 6 and 7 to said motor 15 is such that said pumps are driven at like speeds and hence maintain a constant proportionality of the volumes of fluids delivered thereby. The drive of the gas pump 5, on the other hand, includes a speed changing device such as the opposed cone pulleys 20 10, 11 and the shiftable idler 12 illustrated, whereby the proportion of gas to air delivered may be varied. Obviously, if desired, the gas pump 5 might be driven at a speed 25 constant with respect to the motor speed and the speed of the air pumps 6 and 7 varied with reference thereto.

Test gas is admitted to the pump 5 through a conduit 13 at a pressure equal to 30 the intake pressure of the pumps 6 and 7. In practice a pressure regulating device 14 provides for delivery of the gas to the pump intake at atmospheric pressure, whereas the air pumps 6 and 7 which draw from the 35 interior of tank 8 are also supplied at atmospheric pressure by means of a passage 15 which connects the interior of said tank with the outer air.

Said pressure reducing device 14 preferably comprises a barrier 16 located within 40 the conduit 13 and provided with a reduced opening 17, and an open ended branch pipe 18 connected with said conduit on the pump side of said barrier. In operation the barrier 16 serves to restrict the flow of gas 45 therebeyond to a value which is able to escape through the pipe 18 without raising the pressure upon the pump side of said barrier above atmospheric pressure, whereas 50 the outward flow of gas through said pipe 18 effectively prevents induction of air into the pump. The gas so issuing from the pipe 18 is ordinarily ignited and burned to avoid 55 pollution of the surrounding air. Such continuous efflux of gas in appreciable quantities from said tube further serves to insure 60 that the test gas drawn into the pump constitutes a true sample of the main supply undergoing test. Also the gas in passing 65 through the pump is caused to attain the temperature of the sealing liquid within the tank 8, to which temperature the fluids handled by the pumps 6 and 7 are also subjected, all of said pumped fluids being also 70 subjected to like intimate contact with such

sealing liquid and hence becoming saturated therewith at such common temperature.

Thus provision is made for supplying the air and gas to the device 1 under like conditions of temperature, pressure and saturation and for maintaining a constant proportioning of the delivered volumes of combustion air and cooling air, while providing for relative variation of the proportion by volume of the delivered gas, the proportioning of such fluids, moreover, being unaffected by variations in speed of motor 9.

Hence, assuming such proportioning of the three fluids as to effect complete chemical union of the two reactive gases and complete absorption by the cooling fluid of the heat so liberated, it is apparent that any variation in heating value of the gas will effect a corresponding and proportional variation in the consequent temperature rise of 85 said cooling fluid. Also if the relative rate of supply of gas and air be varied, by shifting the idler 12, to compensate for such variation in heating value of the gas, the character and degree of such shifting constitutes 90 an accurate measure of the character and degree of such variation, whereas such variation in rate of supply serves to maintain the proportions suitable for complete combustion and absorption as aforementioned. 95

For example, assuming that for a given sample of gas and a given setting of the idler 12 the cooling air shows a temperature rise of 10°, such temperature rise will obtain even though the speed of motor 9 be 100 doubled, such change serving merely to double the rates of delivery of all three fluids without changing the proportions thereof. On the other hand assuming the heating value of the sample of gas to be reduced to 105 one half of that formerly assumed, the relative speed of the several pumps as determined by the position of the idler remaining unchanged, the temperature rise of said cooling fluid will be reduced to 5°. Again 110 assume adjustment of the idler 12 to increase the relative speed of gas pump 5 sufficiently to restore the temperature rise of the cooling fluid to its former value it is apparent that the character and amount of 115 such shifting may be indicated and the indicating means calibrated to show the heating value of the gas continuously in B. t. u. or according to any desired or preferred system of units.

Resistance thermometers 19 and 20 are arranged in a known manner with reference to the device 1 for measuring respectively the temperature of the cooling fluid before and after the heat exchange. These resistance 125 thermometers are utilized in a Wheatstone bridge to control a galvanometer 21 having associated with its needle 22 a switch 23, having an operating solenoid 24, which serves, in conjunction with a contact drum 130

25 driven by the motor 9, to control the operating electro-magnets 26 and 27 of a ratcheting mechanism 28. Said ratcheting mechanism in turn is utilized to actuate the 5 idler 12 and also to control the marker of a clock-driven recorder 29.

Obviously temperature responsive devices other than the resistance thermometers may be utilized in conjunction with suitable associated mechanisms for actuating and controlling the aforescribed or similar proportioning and recording means.

In practice the motor 9, switch 23 and the solenoids of ratcheting device 28 are supplied from a suitable source L' , L^2 of either direct or alternating current. The movement of said ratcheting mechanism is preferably communicated through suitable gearing to a screw shaft 30, the latter to co-operate with a non-rotative nut 31 upon which the idler 12 is rotatably carried, whereby operation of said ratcheting mechanism in either direction serves to shift said idler axially of its associated cones, to a 20 proportional degree and in a corresponding direction, to similarly vary the speed ratio of the drive through said cones and hence of the pump 5 to pumps 6 and 7.

The structure and manner of co-operation 30 of the switch 23, the contact drum 25 and the ratcheting device 28 are clear from the drawing, the same being described at length in my aforementioned patent and elsewhere, and as no specific novelty of such individual 35 elements per se is claimed herein, the same will be described only in conjunction with the other elements of the device.

The resistance thermometers are respectively connected to opposite terminals of the 40 galvanometer and to one side of a D. C. supply circuit L^3 , L^4 through a balancing rheostat 32, while resistances 33 and 34 are respectively connected to opposite terminals of the galvanometer and to the opposite side 45 of said D. C. circuit to complete the Wheatstone bridge.

Also a so-called temperature difference resistance 35 is located preferably within the tank 8 and arranged to be connected in series with the resistance thermometer 19 for a purpose to be hereinafter described, a switch 36 providing for completion of the Wheatstone bridge connections either inclusive or exclusive of said resistance 35.

55 Thus assuming such apportionment of the resistance of rheostat 32 between the two sides of the Wheatstone bridge as to effect a balance of the latter having reference to the difference in temperature of the resistance thermometers 19 and 20 effected by heating of the cooling fluid incident to combustion of test gas of a given heating value, and also assuming that the marker of the recorder be properly positioned with respect to a reference point or line upon the

chart to correspond with such given heating value of the test gas, any variation of such heating value and consequent variation in temperature rise of cooling air will cause the Wheatstone bridge to become unbalanced. Thereupon the galvanometer needle becomes deflected in a corresponding direction and to a degree determined by the degree of such variation and the switch 23 acting in conjunction with the contact drum 70 25 is adapted to effect energization of the appropriate operating solenoid of the ratcheting mechanism 28 for operation of said ratcheting mechanism in a direction and to a degree again determined by the character 75 and degree of variation of the heating value of the test gas. The ratcheting mechanism in turn functions to shift the idler 12 in a direction and to a degree suitable for varying the relative speed of the gas pump 5 to cause the latter to supply gas either more rapidly or less rapidly as may be required to restore the preselected difference in temperature between the resistance thermometers and hence to restore the balance of the 80 Wheatstone bridge. Also the ratcheting mechanism, in so functioning, serves to shift the marker of the recorder to indicate the character and value of the proportioning 85 action thus effected, which in turn is a measure of the heating value of the gas, it being remembered that the temperature rise of the cooling fluid varies in direct proportion to the changes in such heating value. Thus the apparatus automatically compensates for 90 variations in temperature difference of the resistance thermometers to thereby maintain such temperature difference substantially 95 constant, and also provides for making a continuous record of the heating value of 100 the test gas.

Assuming the use of ordinary resistance thermometers, constructed of nickel wire or the like, the temperature resistance characteristic of such thermometers increases as 110 the temperature rises, whereby, assuming similarity of material and construction of such thermometers, the one subjected to the higher temperature is adapted to effect a greater increase of its resistance than is 115 effected by the other thermometer if the temperature of each be increased the same number of degrees. Moreover, such difference in the resistance rise of the two thermometers increases as the lower or base 120 temperature is increased, although the actual difference in temperature of the two thermometers be maintained constant, it being remembered that in the present case such base temperature is the temperature of 125 the cooling fluid entering the device 1, which temperature is, as stated, the same as that obtaining within the tank 8.

Thus due to such cause an increase in tank temperature over that obtaining at the time 130

of balancing the Wheatstone bridge will tend to cause the recorder to indicate too high a heating value of the gas, and upon decrease in tank temperature to indicate too low a value. Moreover, such tendencies increase as the tank temperature variation increases.

On the other hand the specific heat of the cooling fluid, if air, rises upon increase of its content of vapor of the sealing liquid, which content in turn likewise increases with a rise in temperature of said sealing liquid. Thus for a higher tank temperature the cooling fluid requires more heat to raise its temperature a given number of degrees than is required at lower tank temperatures, which cause tends to introduce into the regulation and recording action an error similar but opposite to the thermometer error.

Also the heating value of a given volume of the test gas decreases upon increase in the degree of dilution thereof with vapor of the sealing liquid, that is to say, upon increase in tank temperature, the resultant error being cumulative with that due to the aforementioned variation in specific heat of the cooling fluid.

Thus in the present instance, the tendencies to error due to variation in vapor content of the gas and the cooling fluid tend to offset that due to variation in temperature-resistance coefficient of the resistance thermometers, but obviously, in the absence of special provisions, strictly accurate results will be obtained only if the opposing tendencies to error are of equal value, which condition will seldom arise in practice.

However, the temperature difference resistance 35, provided with circuit connections as described and located preferably within the tank 8 for subjection to the temperature conditions there obtaining, may be designed and calibrated to compensate for all of the aforementioned tendencies to error, or more properly for the differential of the opposing tendencies.

Said temperature difference resistance is preferably composed of resistive material, such as a suitable combination of nickel, 50 copper and manganin, or certain of such substances, so proportioned and combined that the temperature resistance coefficient of said resistance is adapted to vary, under varying temperature conditions in a manner to compensate for the corresponding 55 variations in temperature-resistance coefficient of the resistance thermometers. Ordinarily the temperature difference resistance may be so designed that its temperature-resistance coefficient varies in the same sense 60 as that of the resistance thermometers but at a lesser rate. However, under certain conditions, as where relatively high temperatures are involved, it may be necessary or 65 desirable to employ a material such that the

temperature-resistance coefficient of said resistance is adapted to vary in a sense which is the opposite of that of the coefficient of the resistance thermometers, or to employ an arrangement to produce a similar effect. 70 Moreover, the value of said resistance is designed to correspond to the temperature difference which it is desired to maintain between the resistance thermometers, for which reason said resistance has been designated as a temperature difference resistance. 75

In the operation of the device inclusive of said resistance the Wheatstone bridge is first balanced in the usual manner, in the absence of heat in the device 1 and said resistance being excluded from circuit. Upon inclusion of said resistance in series with the resistance thermometer 19 the bridge becomes unbalanced to a degree corresponding to the resistive value of said resistance 85 under the existing temperature conditions. Thus to restore the balance of the bridge, the fluid pumps are operated and the reaction fluids ignited to supply to the cooling fluid sufficient heat to increase the resistance 90 of the thermometer 20 by an amount equivalent to that of said resistance whereupon the apparatus is adapted to function as aforescribed.

If at any time the temperature of the various fluids, as determined by that of the sealing liquid rises above its value at the time of balancing the Wheatstone bridge, the indications effected by the device will tend to vary from the true values due to the three causes aforesdiscussed. However, the temperature difference resistance, if properly designed and calibrated, serves to overcome such tendencies.

It is also possible by suitable selection of material and design, to so modify the temperature-resistance coefficient of one or both of the resistance thermometers as to adapt the same to effect the aforescribed compensating action without the aid of a separate temperature difference resistance, where-as any of the foregoing expedients may, if desired, be utilized for securement of effects different from or additional to those stated.

Since the recorder 29 indicates, in effect, merely the speed ratio of the gas and air pumps, it is apparent that any one of a number of known devices may be subjected to control in accordance with the value of such ratio and so utilized to provide distant indication for recording of the heating value of the test gas.

While the foregoing description relates chiefly to determination of the heating value of a combustible fluid, it is to be understood that the instant method and apparatus are equally applicable to other reactions of the same or different agents and involving either liberation or absorption of heat.

Obviously by slight modification of the

aforedescribed apparatus, the same may, without departure from the fundamental method, be adapted to indicate different calorific effects of the combustion or other chemical reaction involved.

5 Thus if one resistance thermometer be arranged to be maintained at a constant temperature and the other located within the combustion flame, the apparatus is adapted 10 to indicate the degree and character of supply regulation of the various fluids that is required to maintain a constant flame temperature and to regulate for maintaining such constant flame temperature either with 15 or without indication of the heating value of the gas.

Again assuming location of the resistance thermometers respectively within the stream of the combustion fluids prior to combustion 20 thereof and within the stream of combustion products, the combustion fluids being proportioned as described, the device may be adapted to perform regulating and indicating functions similar to those performed 25 by the preferred form of calorimeter.

The afore-indicated adaptability of the method and apparatus to regulation of the supply of the combustion fluids for securing and maintaining a desired calorific effect is 30 inherent in the instant principle of calorimetry which includes regulation and indication or determination of the degree and character of the regulation effected.

What I claim as new and desire to secure 35 by Letters Patent is:

1. The method of calorimetry which comprises effecting a chemical reaction involving a given agent definitely proportioned relatively to another substance and effecting predetermined variations in the relative proportions of such agent and other substance automatically in response to variations in certain calorific effects of the reaction.

2. The method of calorimetry which comprises effecting a chemical reaction involving a given agent definitely proportioned relatively to another substance and effecting predetermined variations in the relative proportions of such agent and other substance 45 automatically in response to variations in value of the difference between a temperature which is a direct function of the reaction and a temperature independent of the reaction.

55 3. The method of calorimetry which comprises effecting a chemical reaction involving a given agent to obtain a temperature which is a direct function of the reaction and utilizing the relation of successive values of 60 the difference between such temperature and a temperature independent of the reaction for effecting automatic definite variation of the proportion of such agent relative to another substance.

65 4. The method in calorimetry of quanti-

tatively proportioning a chemical agent and another substance according to the calorific effect of a chemical reaction involving such agent, which comprises effecting such chemical reaction to obtain a temperature which 70 is a direct function thereof and definitely controlling the relative proportions of such agent and other substance automatically in response to variations in value of the difference between such temperature and a temperature independent of the reaction, to thereby maintain substantial uniformity of successive values of such temperature difference.

5. The method which comprises effecting 80 a chemical reaction involving a given agent, subjecting a separate fluid substance to the calorific effect of such reaction for effecting a heat exchange and varying the relative proportions of such agent and other substance 85 automatically in response to variations in such calorific effect to obtain a given relation of certain successive effects of the heat exchange.

6. The method which comprises effecting 90 a chemical reaction involving a given agent, subjecting a separate fluid substance to the calorific effect of the reaction, proportioning such agent and substance for obtaining a given temperature change of the latter as a 95 result of the reaction, and varying the relative proportions of such agent and other substance automatically in response to variations in such calorific effect to maintain substantially constant the temperature change 100 to which such substance is subjected.

7. The method of proportioning a chemical agent and a separate fluid substance according to the calorific effect of a chemical reaction involving such agent, which comprises subjecting such substance to such calorific effect of the reaction and utilizing variations in the rate of heat exchange thus effected to automatically effect quantitative proportioning of such agent and such substance to minimize variations in the rate of heat exchange under conditions tending to vary the same.

8. The method which comprises effecting 115 a chemical reaction involving given agents, maintaining the supply of one of such agents substantially constant and definitely varying the relative proportion of another of such agents automatically in response to variations in value of the difference between a temperature which is a function of the reaction and a temperature independent of the reaction.

9. The method which comprises effecting 125 a chemical reaction involving given agents, and definitely varying the proportion of certain of such agents relatively to other of the same automatically in response to variations in value of successive calorific effects of such 130

reaction to maintain substantially constant the value of such calorific effects.

10. The method of measurement of the heating value of a combustible fluid which comprises effecting combustion of such fluid with another fluid, effecting a flow of cooling fluid in a heat exchanging relation with the products of combustion, proportioning the supply of certain of the fluids to maintain the resultant temperature rise of the cooling fluid substantially constant and utilizing the effected variations in proportionality as a basis of such measurement.

11. The method of ascertaining the heating value of a combustible fluid which comprises effecting combustion of a quantity of such fluid in heat exchanging relation with a quantity of a different fluid and regulating the quantitative proportioning of such fluids to maintain a substantially constant effect of the resultant heat exchange.

12. The method of ascertaining the heating value of a combustible fluid which comprises supplying under like conditions of temperature, pressure and saturation, test fluid, air to be mixed therewith and a cooling fluid, burning the mixture of test fluid and air in a heat exchanging relation to said cooling fluid, proportioning the supply of said fluids to maintain a given effect of the resultant heat exchange and utilizing the character and extent of such proportioning action for determination of the heating value of the test fluid.

13. In apparatus for supplying fluids or other substances and varying the supply of one substance relative to another according to a calorific effect of a chemical reaction involving certain of such substances, the combination with means to supply such substances and to vary the quantitative proportionality thereof, of control means for the former means responsive to variations in the difference between a temperature which is a function of the reaction and a temperature which is independent of the reaction.

14. In apparatus for supplying fluids or other substances and varying the supply of one substance relative to another according to a calorific effect of a chemical reaction involving certain of such substances, the combination with means to supply such substances and to vary the quantitative proportionality thereof, of control means for the former means, subjected to influence in accordance with the relation of successive values of the difference between a temperature which is a function of the reaction and a temperature which is independent of the reaction, for maintaining substantially a given relation of such successive values.

15. In apparatus for supplying fluids or other substances and varying the supply of one substance relative to another according to a calorific effect of a chemical reaction in-

volving certain of such substances, the combination with means to supply such substances and to vary the quantitative proportionality thereof, of control means for the former means, subjected to influence in accordance with the relation of successive values of the difference between a temperature which is a function of the reaction and a temperature which is independent of the reaction, for maintaining substantially a constant value of such temperature difference.

16. In apparatus for supplying fluids or other substances, varying the supply of one substance relative to another according to a calorific effect of a chemical reaction involving certain of such substances and ascertaining the value of certain of such substances for producing such effect, the combination with means to supply such substances and to vary the quantitative proportionality thereof, of means to act upon said former means in accordance with variations in the difference between a temperature which is a function of such calorific effect and a temperature which is independent of such effect, for causing said former means to maintain substantially a given relation of successive values of such temperature difference, and means utilizing the degree and character of the action of said latter means for ascertaining such value of said certain of such substances.

17. Apparatus comprising the combination with means to supply in definite proportions agents for a given chemical reaction, of associated means operable automatically in accordance with variations in a calorific effect of the reaction to act upon said former means for regulating the supply and proportionality of such agents to maintain substantially constant successive values of such calorific effect of the reaction.

18. The combination with means to supply an agent for a given chemical reaction thereof, of means, including a definitely proportioned medium, subjected to influence in accordance with the relation of successive values of a calorific effect of such reaction to act upon said former means for regulating the supply of said agent to maintain substantially a constant value of such effect, and means to indicate the degree and character of action of said latter means.

19. The combination with means to supply, in definite proportions, an agent for a given reaction thereof and a medium to be subjected to a heat exchange which is a function of the calorific effect of such reaction, of means for proportioning the supply of said agent and said medium in accordance with the relation of successive calorific effects, and means utilizing the degree and character of operation of said proportioning

means for indicating the value of said agent for producing such effect.

20. The combination with means to supply, in definite proportions, an agent for a given reaction thereof and a separate medium to be subjected to a heat exchange which is a function of the calorific effect of such reaction, of means subjected to influence in accordance with the relation of similar successive calorific effects, for proportioning the supply of said agent and said medium to maintain substantially a constant calorific effect.

21. The combination with means to supply, in definite proportions, a plurality of agents for a given chemical reaction thereof, and a medium to be subjected to a heat exchange which is a function of the calorific effect of such reaction, of associated means to act upon said former means for proportioning the supply of certain of said agents and said medium to maintain substantially a constant calorific effect.

22. The combination with means to supply, in definite proportions, a plurality of agents for a given chemical reaction thereof, of associated means operable automatically in accordance with variations in successive values of a calorific effect of the reaction to act upon said former means for definitely varying the proportionality of certain of said agents, whereby successive values of such calorific effect are maintained substantially constant.

23. The combination with means to supply, in definite proportions, a plurality of agents for a chemical reaction thereof, of associated means to act upon said former means, in accordance with the relation of successive values of a calorific effect of such reaction for maintaining substantially a constant value for such effect, and means controllable by said latter means for indicating the value of certain of such agents for producing such effect.

24. Apparatus for determining the heating value of a combustible fluid comprising in combination means to supply said fluid for combustion and also a different fluid at relatively regulable rates and under like conditions of temperature, pressure and saturation, means to influence said former means for proportioning the supply of said fluids to maintain a given relation of successive values of a calorific effect of the combustion and means controllable by said proportioning means for indicating the heating value of said former fluid.

25. Apparatus for determining the heating value of a combustible fluid, comprising in combination, means to supply said fluid for combustion and also a different fluid, at relatively regulable rates, means, including resistance thermometers to be connected in a Wheatstone bridge to influence said

former means for proportioning the supply of said fluids to maintain a given relation of successive values of a calorific effect of the combustion, and means controllable by said proportioning means for indicating the heating value of said former fluid. 70

26. Apparatus for determining the heating value of a combustible fluid, comprising in combination, means to supply said fluid, a different fluid and a cooling fluid, at relatively regulable rates and under like conditions of temperature, pressure and saturation, for combustion of said former fluids and absorption of the liberated heat by said cooling fluid, means for proportioning the supply of said fluids to maintain a given relation of successive values of the resultant temperature rise of said cooling fluid, and means controllable by said proportioning means for indicating the character and 85 extent of operation thereof.

27. Apparatus for determining the heating value of a combustible fluid, comprising in combination, means to supply said fluid, a different fluid and a cooling fluid, at relatively regulable rates and under like conditions of temperature, pressure and saturation, for combustion of said former fluids and absorption of the liberated heat by said cooling fluid, means, including resistance 95 thermometers to be connected in a Wheatstone bridge, to influence said former means for proportioning the supply of said fluids to maintain a given relation of successive values of the resultant temperature rise of said cooling fluid and means controllable by said proportioning means for indicating the heating value of said first fluid. 100

28. In apparatus for ascertaining the heating value of a combustible fluid, the combination with means for effecting combustion of a regulable quantity of such fluid, of resistance thermometers to be connected in a Wheatstone bridge and subjected to temperatures whose difference is 110 a function of calorific effect of such combustion, temperature difference resistance to be connected in circuit with certain of said resistance thermometers and subjected to a temperature which is independent of the 115 combustion, and means controllable by the Wheatstone bridge for indicating the heating value of the fluid.

29. In apparatus for ascertaining the heating value of a combustible fluid, the combination with means for effecting combustion of a regulable quantity of such fluid, of a Wheatstone bridge having certain of its elements adapted to change their resistance under variable temperature conditions and subjected to temperatures whose difference is a function of a calorific effect of such combustion, said elements being constructed and arranged to maintain substantially a given relation of their respec- 130

tive temperature-resistance characteristics throughout the working range, and means controllable by said Wheatstone bridge for indicating the heating value of the fluid.

30. The method which comprises the step of normally effecting a flow of combustible fluid and a flow of fluid to support combustion thereof in predetermined proportions, ascertaining the total heating value 10 per unit volume of said combustible fluid, and varying the proportionality of said flows of fluids automatically in response to variations in such total heating value.

31. The method which comprises effecting 15 separate flows of fluids one of which is combustible and the other of which is adapted to support combustion thereof, normally maintaining a predetermined proportionality between the volumetric rates of flow 20 of said fluids, ascertaining the instantaneous calorific value per unit volume of said combustible fluid, and definitely varying the volumetric proportionality of said flows of fluids automatically in response to variations 25 in such calorific value.

In witness whereof, I have hereunto subscribed my name.
